UNITED STATES PATENT OFFICE

1,986,803

CLIP BROOCH

William S. Frink, New York, N. Y.

Application September 9, 1933, Serial No. 688,718

2 Claims. (Cl. 63—20)

This invention relates to brooches and has for an object to provide a device of this character with a main ornamental body and a number of ornaments adapted to interchangeably slide into 5 a frame formed in the main body.

Another object is to provide means for automatically securing the ornaments "in position" when slid into the frame. Another object is to furnish the main ornamental body with a hinged 10 flap carrying garment engaging elements, so that the device may be worn as a clip brooch.

In the drawing accompanying this specification I have shown by way of illustration a practicable embodiment of my invention, in which 15 drawing:

Figure 1 is a face view of the complete brooch. Figure 2 is a longitudinal section of brooch shown in Figure 1.

Figure 3 is an underside view of the body portion only of the brooch, the hinged flap being shown in its open position.

Figure 4 is a central longitudinal section of Figure 3.

Figure 5 is an under side view of an interchangeable slide.

Figure 6 is a side view of such slide, and Figure 7 is a cross-section taken on a plane at about the line 7—7 of Figure 3.

The main body 10, of the brooch is intended to 30 be decorated or ornamented in harmony with prevailing ornamentation, being conventionally represented, for instance, at 11 and at 12.

There is shown hinged to the rear of this ornamental main body member 10 a flap 13, furnished 35 with garment engaging elements illustrated in the form of sharp pins 14. The hinge illustrated is composed of a pair of square bosses 15 carried by body, and three bosses 16—16 and 17 carried by the flap, the boss 17 being shown disposed between the boss 15, and the bosses 16 disposed outwardly thereof. There are shown set off from the flap 13 a pair of spring fingers 18 for engaging the squared faces of the bosses 15 for holding the flap in either its closed, Figure 2, 40 position or in its opened, Figures 3 and 4, position.

For the purposes of my invention the body member is formed as an open ended rectangular frame, there being two longitudinal side members 19, and a member 20 at the inner end, the 45 other or outer end being shown open at 21. A groove 22 is formed in the faces of these side and end members, forming ways for interchangeably receiving slides, one of which is illustrated dismounted in Figures 5 and 6, and in position in 50 Figures 1 and 2. The slide illustrated in the

drawing is in the form of a setting, having a rim 24 in which is to be mounted some ornamental body 25, which may be a semi-precious stone.

The principal purpose of this invention is to make up these devices with, for instance, a diamond design ornamenting the main body member, and supply with this a number of interchangeable slides, in which are mounted ornamental bodies 25 of various and contrasting 10 materials and colors. So that the owner of a brooch may readily change its color or ornamental effect to suit almost any occasion or garment color scheme.

The slide carries at each side a flange 26 for 15 running in the longitudinal parts of the groove 22. These flanges merge at the inner end of the slide in a flat plate 27, the edge 28 of which plate is intended to seat in the portion of the groove 22 which is formed in the frame end 20. 20

The two side members 19 of the frame are shown connected by a flat cross-bar 29, having a depression 30 in its central part. This bar is preferably located toward the inner portion of the open frame. The plate 27 is shown slotted 25 at 31 for setting off a spring 32, having a straight front edge 33, from the front center of which projects a finger piece 34. When the slide is in position and fully entered in the frame, with the edges 26 and 28 in the groove 22, the spring 30 32 drops down behind the cross-bar 29, or inwardly of it, securely fastening the slide to the main body member. The finger piece 34 partly is in the depression 30, its front or other end, however, overcharges the bar and is in position 35 for ready engagement outwardly of the cross bar by the finger for releasing the spring. It will be obvious from an inspection of the drawing in connection with the foregoing description that in removing and in replacing the interchangeable slide, the slide can be held between the thumb and finger outwardly of parts disposed crosswise of its path of movement.

Although I have shown but one embodiment 45 of my invention as an illustrative example of my invention, it is to be understood that changes may be made within the scope of my claims without departing from the spirit of my invention.

Having thus described my invention, what I claim and desire to secure by Letters Patent is:

1. In a brooch, the combination with a body member formed as an oblong frame having two sides and a closed end, the other end being open there being grooves formed in the faces of the sides and closed end, a cross bar extending from 55

side to side of the frame, and formed with a central depression, and a flap furnished with gripping devices and hinged to the body member and constituting therewith a garment clip, of an ornamental slide adapted to enter the frame from the open end and to occupy the said grooves, and a catch for holding the slide member within the frame, and comprising a forwardly directed spring set off by slits formed in the slide, there being a forward extension from the central end of the spring, formed on its under side with a finger engaging protrusion, the organization being such that when the slide is moved upon the grooves and is fully entered into the frame, the inner end of the slide is under the ornamental portion of the body member, the finger engaging protrusion occupies the central depression in the cross bar, and the forward end of the spring is at the inner side of the cross bar.

2. In a brooch the combination with a body member formed as an oblong frame having two sides and a closed end, the other end being open, there being grooves formed in the inner faces of the sides, a cross bar extending from side to side of the frame, of an ornamental slide adapted to enter the frame from the open end and to occupy the said grooves, a catch member on said ornamental slide having a portion for engaging the said cross bar to lock the slide within said frame, and means at the outer side of said cross bar for releasing said catch member whereby upon releasing the catch and removing the slide and in replacing the slide, the slide can be held between the thumb and finger outwardly of the said cross bar.

WILLIAM S. FRINK.
